Arthur G. Hatch,

By J. Anthony Umina
Atty.

UNITED STATES PATENT OFFICE.

ARTHUR G. HATCH, OF DULUTH, MINNESOTA.

CONCRETE BLOCK AND WALL.

Application filed November 10, 1921. Serial No. 514,287.

To all whom it may concern:

Be it known that I, ARTHUR G. HATCH, a citizen of the United States, residing at Duluth, in the county of St. Louis and State 5 of Minnesota, have invented certain new and useful Improvements in Concrete Blocks and Walls, of which the following is a specification.

This invention relates to a new and improved concrete block and wall design, and more particularly to a block and wall design in which an inner wall forming material, when secured to the block, provides an additional wall air space.

15 A number of types of wall blocks such, for example, as those shown in my prior application, Serial No. 436,638, filed January 12, 1921, are adapted to form walls having horizontally extending air spaces. These 20 and other blocks of the same general type, however, provide but a single series of spaces.

It is highly desirable, in extreme climates, to provide a plurality of series of wall spaces 25 in order to better insulate the buildings. Further, where inner wall forming material is applied to the block wall, it is often desirable to space this material from the wall in order to prevent discoloration due 30 to dampness in the wall.

In general, methods of securing inner walls to concrete blocks comprise casting wood or similar material in the blocks when formed; the inner wall or its supporting 35 furring being nailed or otherwise secured to these wood pieces. Such constructions are undesirable in that they complicate the block manufacture, and further, in that they render construction not fire-proof.

40 It is an object of the present invention to provide new and improved wall block and wall construction adapted to provide for ready attachment of inner wall forming material, and further adapted to space such 45 inner wall from the main body of the block wall.

It is an additional object to provide construction in which the inner wall forming material cooperates with the block wall to 50 form an additional series of air spaces.

It is also an object to provide blocks which are simple in design and which can be readily constructed in large quantities.

55 Other and further objects will appear as the description proceeds.

Broadly, my invention comprises a wall

consisting of blocks adapted, when faced toward each other in opposed series, to form a wall having air spaces therein. It further comprises blocks having spaced portions formed thereon extending outwardly from the face of the block for the purpose of separating from the wall face, inner wall forming materials secured thereto.

In the preferred form, these spaced portions are adapted to register in adjacent blocks and form continuous pilasters. These pilasters, together with the block wall and inner wall, form air spaces. In the preferred form, the pilasters are formed of material adapted to receive nails.

I have illustrated a preferred embodiment of my invention in the accompanying drawings, in which—

Figure 1 is a perspective view showing a 75 fragment of wall constructed according to this invention;

Figure 2 is a horizontal section of such wall, the wall having inner wall material secured thereto;

Figure 3 is a section taken on line 3—3 of Figure 2; and

Figure 4 is a section taken on line 4—4 of Figure 2.

Referring now to the drawings, blocks 5, forming a wall as shown, are provided with the narrow flanges 6 extending along one long side of the block, and wide flanges 7 extending along the parallel side of the block. The ends of the block are formed with vertically extending thickened portions 8. As shown in the drawings, the blocks are preferably placed in the reverse position in the walls so that the narrow flange on one block is opposite the wide flange on the opposite block. As clearly appears in Figures 3 and 4, a series of horizontal air spaces are thus formed in the wall. Those blocks adapted for use upon the inner side of the wall, are provided upon their outer face 100 with vertically extended projections 9. These projections are spaced apart and stand outwardly beyond the contour of the main body of the wall. The projections are so spaced that when built into the wall, they 105 will register with those upon adjacent blocks and form continuous, vertically extending pilasters.

In the preferred form, the body of the block is formed of any usual concrete mixture while the pilasters are formed of slag, sawdust, cinder concrete, or any other nail-

able concrete so that the wall forming material may be nailed thereto. This wall forming material may comprise wall board or expanded metal or furring of any kind.

6 It will be observed that the wall indicated at 10 in the drawings is spaced from the main body of the wall by the pilasters to form vertically extending air spaces 11. The completed wall thus provides two series 10 of air spaces, one extending horizontally and one extending vertically. The wall thus affords very complete insulation and the inner wall surface will not be affected by dampness. The complete wall contains 15 nothing but fire-proof materials.

My construction is capable of many modifications to adapt it to varying conditions and it is my intention to cover all such modifications coming within the spirit and scope 20 of the appended claim.

I claim:

A wall comprising building blocks placed in oppositely faced spaced parallel courses, the body of the blocks being formed with similar inner faces, the opposite courses 25 forming horizontally extending air spaces between them, the outer faces of the blocks on at least one side of the wall having vertically extending pilasters formed thereon, the pilasters upon superposed blocks forming 30 vertically extending pilasters continuous for the height of the wall, and a sheet of inner wall forming material secured to said pilasters, vertically extending air spaces being formed between the blocks, pilasters and 35 sheet material.

Signed at Duluth, Minnesota, this 24 day of October, 1921.

ARTHUR G. HATCH.
